UNITED STATES PATENT OFFICE.

WILLIAM EICHELBERGER, OF PIERCE, WEST VIRGINIA, ASSIGNOR OF ONE-HALF TO
GEORGE B. SOMERVILLE, OF JOHNSTOWN, PENNSYLVANIA.

COMBINED EGG BOILER AND POACHER.

1,354,385.

Specification of Letters Patent. Patented Sept. 28, 1920.

Application filed July 21, 1919. Serial No. 312,347.

To all whom it may concern:

Be it known that I, WILLIAM EICHELBERGER, a citizen of the United States of America, residing at Pierce, in the county of 5 Tucker and State of West Virginia, have invented new and useful Improvements in Combined Egg Boilers and Poachers, of which the following is a specification.

The present invention comprehends generally improvements in cooking utensils and more particularly relates to an egg boiler and poacher.

It is the principal aim and object of this invention to provide a device of the above 15 mentioned character designed to either boil or poach eggs as desired and in addition is capable of being used in other capacities of a like nature, the construction being novel and embodies generally a support and a plurality of holders designed to be removably supported therein.

As an additional and equally important object this invention contemplates the provision of a device of the above mentioned 25 character wherein the holders are novel in construction and the covers or caps therefor are designed with perforations capable of being closed so as to adapt the holders for boiling or poaching as desired.

Among the other aims and objects of this invention may be recited the provision of a device of the above mentioned character with a view to compactness and wherein the 30 number of parts are few, the construction simple, the cost of production low and the efficiency high.

Other objects as well as the nature characteristic features and scope of this invention will be more readily understood from 40 the following description taken in connection with the accompanying drawings and pointed out in the claims, forming a part of this specification.

The invention is clearly illustrated in the accompanying drawings, in which:—

Figure 1 is a top plan view of the improved device.

Fig. 2 is a side elevational view thereof.

Fig. 3 is an enlarged vertical sectional 50 view of one of the holders.

Fig. 4 is a top plan view thereof, and

Fig. 5 is a bottom plan view of the cap of one of the holders.

Similar characters of reference are em-

ployed in all of the above described views 55 to indicate corresponding parts.

Referring now, more particularly to the accompanying drawings, there is provided a support generally designated by the numeral 1 including a plate-like body 2 which may 60 be of a circular form having depending supporting legs 3 and further provided with a plurality of openings 4 in which are removably received and supported egg holders 5. A grip handle 6 is connected centrally of the plate body 2 to facilitate the handling of the device such as placing it in and removing it from a cooking receptacle.

In the present instance each of the improved holders 5 consists of a cylindrical body 7 having a tapered and closed bottom 8 and having the upper end enlarged to provide an exterior annular supporting shoulder 9 and a threaded neck 10 with 70 which is removably engaged a correspondingly threaded flanged cap 11. The top of the cap is provided with circles of perforations 12 while coacting therewith is a closure disk 13 correspondingly perforated as at 75 14 and rotatably arranged beneath the top. This mounting is effected by means of a pin 15 which is carried centrally of the disk and rotatably arranged through the top and centrally thereof. Bearing collars 16 are 80 formed on the pins 15 as are finger loops 17 which facilitate the turning of the disks so that the perforations 12 will be closed by the disks for the poaching of eggs in 85 the holders when the latter are in the support 1 or arranged so that the perforations 14 aline with the perforations 12 for the boiling of eggs, as is apparent.

To facilitate the removal of poached eggs from the holders, a cutter 18 is employed 90 and is preferably formed from a single piece of wire the upper end of which is connected with the under surface of the top of the cap so that the cutter depends therefrom, being positioned in close relation to 100 the inner surface of the body of the holder and having the lower portion curved to conform to the bottom of the body so as to facilitate an effective cutting or removal of the egg from the holder, the cutter of course 105 being moved about the inner surface of the body thereof upon the turning of the cap.

From the foregoing description it is be-

lieved that a further detailed description of the operation of the invention is entirely unnecessary. Likewise it is believed that the advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a limited sense. It is also to be understood that the language used in the following claims is intended to cover all the generic and specific features of the invention herein described and all statements of the scope of the invention which as a matter of language might be said to fall therebetween.

What is claimed is:—

1. A device of the character described including in combination with a support having openings therethrough, of a plurality of egg holders for removable disposition through the openings, each of the holders including a cylindrical body having a ta-

pered and closed bottom and having the upper portion enlarged to form a supporting shoulder and a neck, a closure cap on the neck, and a cutter carried by and depending from the cap.

2. A device of the character described including in combination with a support having openings therethrough, of a plurality of egg holders for removable disposition through the openings, each of the holders including a cylindrical body having a tapered and closed bottom and having the upper portion enlarged to form a supporting shoulder and also formed with a threaded neck, a threaded flanged cap for detachable engagement with the neck and provided in its top with circles of perforations, a correspondingly perforated disk rotatably mounted on the under surface of the cap and designed to control the passage of water into the body of the holder, and a cutter connected to and depending from the cap and arranged adjacent to the inner surface of the walls of the body.

In testimony whereof I affix my signature.

WILLIAM EICHELBERGER.
